UNITED STATES PATENT OFFICE.

PAUL RUBEO LISA, OF NEWARK, NEW JERSEY.

COMBINATION DISH WASHER AND STERILIZER.

No. 831,084.

Specification of Letters Patent.

Patented Sept. 18, 1906.

Application filed October 16, 1905. Serial No. 282,915.

To all whom it may concern:

Be it known that I, PAUL RUBEO LISA, a subject of the King of Italy, residing at Newark, in the county of Essex and State of New Jersey, have invented certain new and useful Improvements in a Combination Dish Washer and Sterilizer, of which the following is a specification.

The present invention pertains to an improvement in dish-washers, and more particularly to a combination dish washer and sterilizer.

The object of my invention is to provide a dish-washer wherein a large number of dishes of various shape and sizes will be washed in a minimum space of time by fine jets of hot and cold water and through the medium of hot air conveyed into the apparatus from a cooking-stove will also be sterilized and dried in a most effective manner.

My invention is illustrated in the accompanying drawings, in which similar reference-letters denote corresponding parts, and in which—

Figure 1 is a sectional elevation of my apparatus; Fig. 2, a top plan thereof, the cover being partly broken away to show the inner parts; and Fig. 3 is an inclosed cross-section through the winding pipe and a longitudinal section through one of the nozzles having a perforated tip.

The dish-washer comprises a casing or receptacle *a*, which may be made of any suitable material, as sheet-iron or the like, and may assume various forms and proportions. The casing is provided with a cover *b*, hinged thereto and adapted to be hermetically closed. For this purpose I prefer to use a washer-ring *c*, of suitable material, as asbestos or the like, which I attach to the under surface of the cover or to the upper edge of the box. A little above the bottom of the receptacle a perforated sieve-shaped intermediate bottom *d* is arranged and attached to the walls of the receptacle. This perforated bottom serves as a support for plates or like dishes. The free space *e* between the perforated bottom and the bottom of the receptacle serves to receive all extraneous matter from the dishes, which can be discharged from time to time through the discharge-pipe *f*, provided with a cock *g*.

Within the receptacle *a* and at some distance from the perforated bottom *d* a wind-

ing tube *g* is arranged in a horizontal plane 55 to extend from one end of the receptacle to the other and from the front wall to the rear one. One end of this winding pipe is closed, while the other communicates with the pipe *h*, branched off an outer pipe *i*, which is 60 adapted to be connected with the hot and cold water supply pipes and which has a cut-off *j*.

Projecting from the perforated bottom *d* are, in the spaces between each two windings 65 of the pipe *g*, transversal walls *k*, arranged adjacent to one of the windings and leaving a larger space between themselves and the opposite winding. These walls *k* serve as supports for the plates or similar dishes, which 70 are placed in the said spaces with their backs leaning against said walls *k*. In addition to the back walls there are in each space between the windings lateral supports *l*, formed by ribs projecting longitudinally from 75 the back walls *k*, or, as shown in the drawings, by short partition-walls projecting upward from the intermediate bottom *d*. Both the back walls *k* and the partition-walls, if the latter be adopted, are perforated or 80 sieve-shaped, as the bottom *d*. The back walls *k* and the ribs or partitions *l* form compartments, each of which is adapted to receive a single dish in tilted position with its back leaning against the wall *k* and its inside 85 exposed to the opposite winding of the tube *g*. The latter is provided with nozzles *m*, projecting laterally from each of the windings to face the front and back of the dishes distributed in the apparatus in the aforesaid 90 manner. The winding tube *g* is preferably arranged at such a level that it will lie approximately in the middle of the dishes. The nozzles *m* are of a conical shape and have perforated tips. The perforations are 95 made as small as possible to allow very fine streams of high pressure striking the inside and outside of the dishes, whereby all foreign matter will be removed from the latter.

Apart from the arrangement described for 100 washing plates or similar dishes, the receptacle may be provided with one or more subdivisions or compartments for other dishes, as cups, glasses, or the like. In the drawings I have shown one more compartment 105 for such other dishes. This second compartment is formed by a perforated flange or support *n*, projecting inward from the walls of the

casing *a* all around the inner circumference of the latter. The width of the said support *n* is sufficient to accommodate one or more rows of dishes. Between the edges of the 5 said perforated support *n* a free space is formed to allow access to the lower compartment holding the plates. To secure the cups, glasses, or like dishes in proper position, I arrange and attach receptacles *o* upon the 10 support *n*, which I form of wire-netting, perforated sheet-iron, or any other suitable material, the said receptacles being of equal or different sizes and shape to receive similar or different dishes. Extending parallel and 15 centrally above and below the support *n* are pipes *p p'*, which, as the winding pipe *d*, are provided with nozzles *q q'* of similar construction as the nozzles *m*. The nozzles *q* of the upper pipe *p* project from the lower surface 20 thereof toward the interior of the dishes, and the nozzles *q'* of the lower pipe *p'* project from the upper surface thereof toward the exterior of the dishes.

The pipes *p p'* are at one end similarly to 25 the pipe *d* brought in communication by branch pipes *r r'* with the exterior pipe *i*.

The sterilizing apparatus comprises a tightly-closed casing *s*, formed at the outside of the receptacle *a* and attached to the walls 30 thereof. The part of the wall of the receptacle *a* which is inclosed at the outside by the casing *s* is cut out and the opening is covered by a piece *s'* of porous material. The casing *s* forms an antechamber for hot air admitted 35 into it through a pipe *t*, having a cut-off cock *t'* and being adapted to be connected in a suitable manner with the cooking-stove or any other heat source. The casing *s*, forming the antechamber for the hot air may be 40 omitted and the pipe *t* directly affixed to the wall of the casing *d* to terminate in the opening thereof in front of the porous partition *s'*.

The object of the porous partition *s'* is to 45 retain soot, dust, and other foreign substances contained in hot air coming from the stove and permit only purified air to enter the receptacle *a*.

Attached to one of the walls of the receptacle *a* may be a glass water-gage *u* to show 50 the level of the water contained in the receptacle.

The mode of operation of the apparatus is as follows: When the dishes are properly distributed in the receptacle *a* and the cover *b* 55 tightly closed, the cock *j* is opened, permitting simultaneously or alternately hot or cold water to flow through the pipes *g, p*, and *p'*, from which it will in fine jets strike the dishes inside and outside. The perforated partitions *k l*, and the perforated or wire-netting casings will permit the streams of water to 60 wash the dishes at the outside. After the washing is finished the cocks are cut off and the water allowed to flow off through dis-

charge-pipe *f* and cock *g'*, the cock *t'* of the 65 hot-air pipe *t* is opened, and hot air admitted into the receptacle, which will not only rapidly dry the dishes, but by reason of the high degree of heat also thoroughly sterilize them.

As stated in the beginning, the receptacle 70 *a*, the perforated supports *d n*, partitions *k l*, and casings *o* may be made of any suitable material. I prefer, however, to use herefor galvanized sheet-iron.

I do not restrict myself to the construction 75 specified and shown, as various changes may be made in the different parts of the apparatus without departing from the principle of my invention.

What I claim, and desire to secure by Let- 80 ters Patent, is—

1. A combination dish washer and sterilizer comprising a receptacle having a cover to be hermetically closed, an intermediate perforated bottom or support above the bottom of 85 the receptacle forming therebelow a space for extraneous matter, a discharge-pipe leading from said space outward, a winding pipe arranged horizontally above the perforated support and communicating at one end with 90 a hot and cold water supply pipe, the spaces between the windings being adapted to receive plates or like dishes which will rest in a tilted position upon the perforated support, conical nozzles laterally projecting from the 95 windings of the pipe toward the inside and outside of the plates said nozzles having fine-spray tips, means for holding the plates in proper position, a hot-air casing attached to the main receptacle, hot-air-supply pipe terminating in said casing, said casing having an opening leading into the receptacle and a porous partition covering said opening, substantially and for the purpose as specified. 100

2. A combination dish washer and sterilizer comprising a receptacle having a cover to be hermetically closed, a perforated intermediate bottom or support above the bottom of the receptacle, a winding pipe arranged horizontally above said perforated support, the 105 spaces between the windings of the pipe being adapted to receive the plates, conical nozzles projecting from the windings toward the inside and outside of the plates, a second perforated support extending above the winding pipe and around the inner circumference of the receptacle, leaving a free space between its inner edges to allow an access to the winding pipe, pipes running parallel and above and below said second support, the upper 110 pipe having conical nozzles with spray-tips projecting downward and the lower pipe having similar nozzles projecting upward, the said second support being adapted to hold cups, glasses or similar dishes, means to secure the said dishes in proper position upon the support, all pipes of the receptacle being 115 in communication with an external pipe 120

adapted to be connected with the hot and cold water supply, a hot-air supply, the receptacle having an opening in which the hot-air supply terminates and a porous partition covering said opening, and a glass water-gage, substantially and for the purpose as specified.

In testimony whereof I affix my signature in presence of two witnesses.

PAUL RUBEO LISA.
